UNITED STATES PATENT OFFICE.

WILLIAM A. PERRY AND GEORGE D. TOY, OF SIDNEY, OHIO, ASSIGNORS TO THE SIDNEY STEEL SCRAPER COMPANY, OF SIDNEY, OHIO, A CORPORATION OF NEW JERSEY.

SCRAPER.

Application filed May 11, 1925. Serial No. 29,427.

This invention relates to wheel scrapers.

One of the principal objects of the invention is to provide a wheel scraper having means whereby the depth of cut may be varied as desired.

Another object of the invention is to provide novel means for assisting the operator in returning the scoop from scraping position to the carrying or transporting position.

Still another object of this invention is to provide novel and improved means for suspending and operating the scraper pan or scoop.

A further object of this invention is to construct a wheeled scraper which can satisfactorily be operated in tandem behind a tractor or other type of engine.

These, with a number of other objects and advantages will be apparent from the following description of a preferred embodiment of the invention, reference being had to the accompanying drawings, in which:

Fig. 1 is a plan view of a scraper constructed in accordance with the invention;

Fig. 2 is a side elevation of the scraper shown in Fig. 1, in mid position with the operating lever lowered almost to latching position for transporting or carrying a load of material, with certain parts omitted to more clearly illustrate the details of construction;

Fig. 3 is a view similar to Fig. 2, but showing the scoop lowered for filling or scraping;

Fig. 4 is a side elevational view of the scraper, the mechanism having been actuated to cause dumping of its load;

Fig. 5 is an enlarged elevational view of the scoop and associated parts showing the method of suspension, one wheel being removed to more clearly disclose certain details of construction;

Fig. 6 is a detail view of parts of the suspension elements; the view being along the line 6—6 of Fig. 5, and having some parts broken away to more clearly illustrate others;

Fig. 7 shows the scraper adjusted for quick filling; and

Fig. 8 is a detail of the adjustable drag hook.

As showing a preferred embodiment, this

invention comprises an arched axle 10 shaped somewhat in the form of an inverted U. This axle 10 is preferably formed from a square section of metal, provided at each end with a rounded portion 11, forming a journal for the wheels 12.

Rigidly secured to the axle 10 by means of a U-bolt 15 is a tilting lever 16, commonly called a "Johnson bar." To each of the upwardly extending sides of axle 10 is fastened, by means of a clip 17, a U-shaped suspension yoke or frame 18. This yoke 18 is rigidly fastened to the lever 16 by means of connecting strips or brackets 19. The interconnection of tilting lever 16, yoke 18 and axle 10 is such, as shown particularly in Figs. 3 and 4, that upward movement of the end 20 of lever 16 will cause rotation of axle 10 within wheels 12 to swing the yoke 18, and the arched portion of the axle, forwardly.

Rigidly clamped upon the horizontally arranged portions of axle 10, by means of a bolt 25, as clearly shown in Figs. 5 and 6, are guide or cam members 26. Each guide 26 is provided with a slot at 27 within which is positioned a roller 28, turning upon a pin 29. Bearing upon the roller 28 and slideable in the slot 27 is fitted a substantially Z-shaped suspension member or gooseneck 30. This member 30 is provided with an upwardly curved portion at 31, which portion rides over the roller 28 when the scoop is moved to its dumping position, as shown in Fig. 4. The rear upwardly bent end 32 of the gooseneck member 30 is provided with an eye 33, into which is hooked one end of a spring 33 from which is suspended the rear end of main frame 41, the latter being provided with suitable eye member 52 to receive the hooked lower end of the spring 33. The forward depending end 37 of gooseneck member 30 is pivotally attached by means of a bolt 40 to frame 41 forwardly of axle 11.

The main frame 41 consists of substantially horizontally disposed side bars extending forwardly and rearwardly on either side of the scoop 62 as best shown in Fig. 1, the forward ends of the side bars being bent inwardly to receive a suitable tongue or draft bar 50 to which the side bars are rigidly secured. Tongue 50 is provided with an adjustable coupling member 51 by

which the scraper is adapted to be connected with a tractor or to the preceding scraper, if the scrapers are operated in tandem. The rearward ends of the main frame side bars 5 are bent inwardly and secured in bracing relationship with one another to a platform 42 carried upon the side bars and upon which platform the operator stands while manipulating the various levers during 10 operation of the scraper. A clevis 43 is secured to the rear of the platform 42 for coupling with the tongue of the next succeeding scraper. Latch 44 is mounted on the platform 42 to receive the tilting lever 15 or Johnson bar 16 and lock the same to the platform when it is desired to transport a load of material.

It will be observed from the above description that the load caused by pulling a 20 number of scrapers in tandem is transmitted through the rigid and well braced main frames 41. It is also seen that in making a turn, each scraper is caused to follow substantially in the track of the one preceding, 25 thus permitting a number of scrapers to be operated in tandem even though the available room for maneuvering be limited.

A scoop 62 is suspended below the axle 10 and between the side bars of the main 30 frame 41, and for this purpose upwardly extending supporting arms 61 are rigidly secured to the side walls of the scoop 62, these supporting arms being pivotally connected at their upper ends by means of bolts 60 35 with the forwardly extending arms of the yoke member or frame 18. The scoop 62 is also provided with side brackets 63 by which it is pivotally connected at 64 with the side bars of the main frame 41. To each 40 side wall of the scoop 62 adjacent its forward end is rigidly secured a bracket 70 having a hook 71 mounted pivotally thereon, the hook portion thereof, under some operative positionings of the apparatus, lying 45 in the plane of the catch 72 secured to and extending downwardly from the frame 41. The pivoted hook 71 is connected by link 73 to the forwardly extending arm of frame 18, the arrangement of the parts being such that 50 when the tilting mechanism is operated to drop the scoop 62 into its loading or scraping position, as illustrated in Fig. 3, the pivoted hook 71 is caused to engage the catch 72. The hook 71 and catch 72 when 55 thus engaged serve to hold the front or cutting edge of the scoop 62 in a definite relation with respect to the main frame 41 and transmit directly to the frame 41, and thereby to the tractor, that load caused by dragging the scoop through the earth.

At the rear of the scoop 62 is fastened a keeper or latch 75 adapted to cooperate with a latch lever or back hook 76 pivoted at 77 upon the brackets 19 which are attached to 65 frame 18. The back hook 76 may be oper-

ated from the platform 42, and when it is engaged with the latch 75 it serves to hold the rear end of scoop 62 from scraping on the ground and cooperates otherwise in the operation of the scoop, as will be more fully 70 explained in the detailed statement of the operation. A spring 79 is connected to the back hook 76 to bias the hook portion thereof towards the latch 75. A retainer 80 is secured to the rear wall of the scoop 62 and 75 extends rearwardly therefrom underneath the yoke member 18, and the rear end of the scoop 62 is thus prevented from swinging upwardly while the Johnson bar and the yoke member 18 are in their horizontal or 80 carrying position.

Attached to the horizontal part of each gooseneck member 30 is a stop 35. This stop 35 is normally positioned slightly out of contact with the rear edge of the guide or cam 26 and limits the forward movement of the gooseneck member 30 in the slot 27. Suitable adjusting slots 36 and fastening bolts 34 are provided in the stop 35 and adjacent portion of the gooseneck member 30 for adjusting the position of the stop 35 and therefore the extent of forward movement of the gooseneck 30 with respect to the cam 26.

Attached to the frame is a standard or support 78 by means of which the operator 95 may support himself when upon the platform.

The operation of the present invention will now be described reference being made first to Figs. 2 and 5 which illustrate the scoop 62 in substantially its carrying or transporting position. It will be noted that the weight of the scoop 62 is transmitted through bracket 61 to the forwardly extending arm of yoke member 18, and therefore 105 tends to rotate the latter forwardly in a counter-clockwise direction. However, such motion of the yoke member 18 is prevented by the hook 44 which is carried by the platform 42 and which engages the lever 16 to 110 lock the yoke member 18 in transporting position, substantially the position illustrated. The weight of the scoop 62 and its contents is thus supported from the yoke member 18 through the supporting arms 61 secured to 115 the scoop 62 forward of the axle 11, and the back hook 76 which engages the rear end of the scoop rearwardly of the axle 11.

To move the scoop 62 into its scraping position the operator unlatches the back hook 76 from the scoop 62, and also unlatches the latch 44 from the Johnson bar, moving the Johnson bar to the position indicated in Fig. 3. Raising the rear end of the Johnson bar, it will be observed, rotates the arched axle 10 forwardly and permits the front end of the yoke member 18 to drop towards the ground. Such dropping of the forward end of the yoke member 18 is accompanied by a 125 dropping of the scoop 62 into contact with 130

the ground, and also such an actuation of the pivoted hook 71 as will cause the latter to engage the catch 72. The main frame, being pivoted to the scoop 62 at the point 64 is thus also free to drop with the scoop 62, such dropping of the main frame 41 being resisted only by the extensible loop consisting of the gooseneck member 30 and the spring 53. The gooseneck member 30 is in 10 effect a lever which rocks about the roller 28 as a fulcrum, the left arm of the lever extending from the pivot 40 to the roller 28 and the right arm of the lever extending from the roller or fulcrum 28 to the hook 33. 15 As the main frame 41 falls, the point 40 of the lever rocks downwardly while the end 33 of the lever rocks upwardly thereby extending the spring 53. Obviously if the stop 35 is moved to the right on the gooseneck 30, the 20 effect is to permit the gooseneck or lever 30 to move farther to the left to increase the length of the left arm 40-29 of the lever while decreasing the length of the right arm 29-33 thereby extending the spring 53 still 25 further and permitting the frame 41 and scoop 62 to drop still more. There being no restraint upon the movement of the Johnson bar 16 the latter of course conforms more or less with the dropping movement of the 30 frame 41 and scoop 62. It will be seen from the foregoing that adjustment of the stop 35 to the right on the gooseneck 30 has a tendency to permit increased dropping of the frame 41 and scoop 62 and therefore to cause 35 a deeper cut of earth; and vice versa, adjustment of the stop 35 to the left tends to decrease the depth of cut of the scoop 62.

It is to be noted that when the scoop is in its scraping position the draft or pull of the 40 tractor is transmitted direct from the main frame 41 to the scoop 62 through the catch 72 and pivoted hook 71, thus relieving other parts of the wheel scraper from undue strain. A further advantage of the present invention 45 is that while the Johnson bar is in its raised position the roller 29 is substantially at its dead center with respect to the axle 11.

After the scoop 62 is loaded, and to position the device for transporting the load, the 50 operator may return it to its carrying position by pulling down the Johnson bar to a position slightly beyond the position shown in Fig. 2, causing engagement of the back hook 76 with the latch 75, and preferably 55 locking the Johnson bar to the frame 41 by means of the latch 44.

In returning the scoop 62 to its carrying position, it will be noted that the operator is assisted by the retractile spring 53 which 60 tends to rock the gooseneck lever 30 about the roller 29 as a fulcrum thereby exerting considerable upward or lifting force on the frame 41 at the point 40. At the same time the lower end of the spring 53 is pulling 65 upwardly on the frame 41 at the point 52.

As already explained, the spring 53 is extended or placed under tension during the movement of the scoop 62 from the carrying position to the scraping position. The spring 53 thus stores potential energy during 70 the dropping movement of the scoop 62 and at a time when little effort is required on the part of the operator, and releases this energy to assist the operator during the upward or lifting movement of the scoop and at a time 75 when considerable effort is required on the part of the operator.

Dumping of the scoop 62 is accomplished by unlatching the Johnson bar at 44, while leaving the latch 76 in position to connect the Johnson bar and the rear end of the scoop, and lifting the Johnson bar to turn the yoke 18 and scoop 62 into the position illustrated in Fig. 4. This dumping operation is assisted by the forward movement of 80 the scraper, since upon raising the Johnson bar 16 the initial effect of this movement is to lower the front edge of the scoop 62, and when it is lowered sufficiently to come into contact with the ground the front edge of 90 the scoop drags, thus effectively arresting the scoop while the other parts of the wheeled scraper move on.

In bringing the scoop 62 to its dumping position the Johnson bar 16, axle 10, scoop 95 62 and other parts connected to move therewith are in effect rotated about the bolt 64 as an axis, the roller 28 riding forwardly under the gooseneck 30. The latter, swinging about its pivot 40 follows and remains in contact with the roller 29 under the influence 100 of the retractile spring 53. Upon still continuous motion of the Johnson bar the roller 28 will engage the notch formed in the gooseneck lever at 81, in which position the gooseneck lever has a tendency to hold the scoop 105 32 in its extreme position as will be apparent from Fig. 4. When it is desired to return the scoop 32 to its carrying position, this may be readily accomplished by pulling 110 down the Johnson bar 16.

Under certain conditions, as for example, when operating in loose or sandy soil, the power required to pull the scraper during the filling operations is less than when the 115 scraper is working in firm soil, and under such conditions it is desirable to fill or scrape more quickly so as to reduce not only the time required for filling but also the travel of the scraper during the filling or scraping 120 operations. Quick filling of the scraper is herein provided for by the adjustable catch or drag hook 72 illustrated in Figs. 7 and 8. Referring particularly to Fig. 8, the frame 41 of the scraper is provided with a bracket 125 member 101 having a slot 102 in one side wall thereof to receive the drag hook 72, the slot being of such dimensions as to permit the drag hook to be slid longitudinally in the slot. The upper end of the drag hook 130

72 is inclined at a slight angle to the main portion of the drag hook and is provided with a plurality of bolt holes 103, 104 and 105 by which the upper end of the drag link 5 may be rigidly bolted to the frame 41.

To more quickly fill the scraper, the forward or cutting edge of the scraper should be lowered to some such position as illustrated in dotted lines in Fig. 7. This results 10 in a deeper cut and a quicker filling of the scraper. From consideration of the above description, and with particular reference to Fig. 7, it will be apparent that since the drag or pull of the tractor is transmitted to 15 the scraper 62 primarily through the pivot bolt 64 and the drag hook 72, any extension or lengthening of the drag hook 72 will permit the forward end of the scoop 62 to rock downwardly from the full line position indicated in Fig. 7 to the dotted line position. The forward or cutting edge of the scoop is thus dropped from the position indicated at 20 106 to that indicated at 107 thereby securing a deeper cut and hence a quicker fill of the scoop. But such downward movement 25 of the forward portion of the scoop carries with it the mud hook 71 to such an extent that, were the drag hook 72 merely lengthened along its original axis, the mud hook 30 would slip out of engagement with the hooked portion of the drag hook, thus resulting in disarrangement and possible damage of the parts of the scraper.

The present invention guards against this 35 contingency by reasons of the peculiar construction and mounting of the drag hook. As illustrated in Fig. 8, when the drag hook is lengthened as by bolting it to the frame through the bolt holes 104 or 103, the rearward end of the drag hook is dropped downwardly as well as simply lengthened. The 40 drag hook has a swinging movement in the slot 102, that is, it swings downwardly about this slot as a center as it is moved backwardly. To accommodate such relative swinging 45 movement of the drag hook in the slot 102 the walls of the latter are curved as indicated at 108 and 109 respectively. When the drag hook has been adjusted in the desired 50 position it may be securely fastened in the bracket 101 by the fastening means indicated at 110, which may consist of a washer and a bolt for holding the drag hook in position 55 in the slot.

While the form of apparatus herein described constitutes a preferred embodiment of the invention, it is to be understood that the invention is not limited to this precise form of apparatus, and that changes may be 60 made therein without departing from the scope of the invention which is defined in the appended claims.

What is claimed is:

1. In a scraper, the combination of a carriage, a frame, a scoop adapted to be moved

into scraping or into carrying position, means for moving the scoop from one said position to the other, and adjustable means for varying the depth of cut of said scoop when in its scraping position, said means including a lever member having pivoted connection at one end with the frame and adapted to rock about a fulcrum on said carriage, yielding means for resisting rocking movement of said lever in one direction, 75 and means for varying the position of said fulcrum with respect to the lever.

2. In a scraper, the combination of a carriage, a scoop adapted to be moved into scraping or into carrying position, lifting lever means for moving the scoop from one said position to the other, and means arranged to store potential energy upon movement of the scoop from carrying toward scraping position and to release energy to assist movement of the scoop from scraping towards carrying position, said means comprising a yielding loop connected to exert its operative effect between the carriage and the scoop and including a rigid lever member having engagement intermediate its ends with said carriage. 90

3. In a scraper, the combination of a carriage having an axle, a frame, a scoop suspended in the frame, and yielding loop means for supporting the frame from the carriage, said loop means including a rigid member in engagement with said carriage and connected to said frame. 95

4. In a scraper, the combination of a carriage having an axle, a frame, a scoop suspended in the frame, and yielding loop means for supporting the frame from the carriage, said loop means comprising a lever member pivotally connected at one end with the frame and cooperating intermediate its ends with the axle of said carriage, and yielding means for connecting the other end of said lever with the frame. 100

5. In a scraper, the combination of a carriage having an axle, a frame, a scoop suspended in the frame, and yielding loop means for supporting the frame from the carriage, said loop means comprising a lever member pivotally connected at one end with the frame and cooperating intermediate its ends with the axle of said carriage, yielding means for connecting the other end of said lever with the frame, means for rocking said axle, and eccentric means carried by said axle for increasing the tension of said yielding means upon rocking of the axle in one direction. 115

6. In a scraper, the combination of a carriage having an axle, a frame, a scoop suspended in the frame, and yielding loop means for supporting the frame from the carriage, said loop means comprising a lever member pivotally connected at one end with the frame and cooperating intermediate its 120

- ends with the axle of said carriage, yielding means for connecting the other end of said lever with the frame, means for rocking said axle, said rocking means being connected with the scoop and adapted upon rocking movement in one direction to lower the scoop and upon movement in the other direction to raise the scoop, and means carried by said axle and engaging the lever member for increasing the tension of said yielding means upon rocking movement in the direction to lower the scoop.
7. In a scraper comprising a draft member, a scoop swingingly mounted in said draft member and a scoop hook member carried by the scoop, a frame hook member carried by the draft member and adapted to cooperate with said first mentioned hook member to limit the downward swinging movement of the scoop, means for adjustably but rigidly securing said frame hook member to the draft means to vary the effective length of the frame hook member, said securing means being so constructed and arranged as to cause dropping of the rearward portion of the frame hook member coincident with the lengthening thereof.
8. In a scraper comprising a draft member, a scoop swingingly mounted in said draft member and a scoop hook member carried by the scoop, a frame hook member carried by the draft member and adapted to cooperate with said first mentioned hook member to limit the downward swinging movement of the scoop, and having a laterally inclined upper end portion, a bracket carried by the draft member having a groove therein through which the frame hook member is adapted to slide, and means for rigidly securing said inclined portion of the frame hook member to said draft means in a plurality of positions.
9. In a scraper comprising a draft member, a scoop swingingly mounted in said draft member and a scoop hook member carried by the scoop, a frame hook member carried by the draft member and adapted to cooperate with said first mentioned hook
- member to limit the downward swinging movement of the scoop, and having a laterally inclined upper end portion, a bracket carried by the draft member having a groove therein through which the frame hook member is adapted to slide, and said groove having curved walls to permit a rocking movement of said draft member therein, and means for rigidly securing said inclined portion of the frame hook member to said draft means in a plurality of positions.
10. In a scraper, the combination of a carriage having an axle, a frame, a scoop suspended in the frame, and means for suspending the frame from said carriage, said means comprising a rigid member pivotally connected to said frame, a guide member on said axle, and a roller carried by said guide member, said rigid member being slidably fulcrumed on said roller.
11. In a scraper, the combination of a carriage having an axle, a frame, a scoop suspended in the frame, and means for suspending the frame from said carriage, said means comprising a rigid member having a substantially horizontal portion fulcrumed and supported on said carriage, a downwardly depending portion on one side of said fulcrum pivotally connected to said frame, and an upwardly extending portion on the opposite side of said fulcrum, and yielding means connecting said upwardly extending portion with said frame.
12. In a scraper, the combination of a carriage having an axle, a yoke frame connected to said axle, a draft frame suspended from said carriage, a scoop, a member rigidly connected to said scoop and pivotally connected to said yoke frame, and a second member rigidly connected to said scoop at the rear of said first-mentioned member and pivotally connected to said draft frame, said members being unconnected with each other.

In testimony whereof we hereto affix our signatures.

WILLIAM A. PERRY.
GEORGE D. TOY.
